ABRASIVE FEEDING MECHANISM FOR
STONE CUTTING MACHINES

Mack H. Owens, Lakewood, and Earl A. Burr, Shaker Heights, Ohio, assignors to the Cleveland Quarries Company, Cleveland, Ohio, a Corporation of Ohio

Application November 27, 1931
Serial No. 577,502

16 Claims. (Cl. 125—12)

This invention relates broadly to stone sawing or cutting machines and more particularly to abrasive feeding mechanism for such machines.

5 The primary object of the invention is to generally improve and render more efficient abrasive feeders for stone saws or cutters, particularly those of the gang type. With this object in view, means of a particularly advantageous character are provided for efficiently distributing the abrasive material fed to the entire gang of saws and for selectively augmenting the quantity thereof fed to each saw, or kerf formed by the saw to thereby, among other advantages, 10 insure efficient work of the saws and prevent retardation of the entire group or gang of saws by one or more lagging saws. The driving mechanism for the feed devices is constructed with a view toward facilitating adjustment and accurate control of the feed, and means are provided for determining at a glance whether or 15 not the feeding mechanism is functioning with respect to each respective saw.

The means for conducting the abrasive material to the saws or cutters are adjustable to accommodate different heights of stone and widths of cuts, and the structure of the feeding mechanism is relatively simple in construction and is endowed with features which render it 20 superior in efficiency over machines of this class as heretofore devised.

The foregoing and other features of novelty and advantage in construction of the improved feeding mechanism will become apparent in view 25 of the following description taken in conjunction with the drawings, wherein—

Fig. 1 is a view in side elevation of a gang saw or cutter and co-operating feeding mechanism illustrative of the features of the invention;

40 Fig. 2 is a view in end elevation;

Fig. 3 is a plan view of the feeding mechanism, and

Fig. 4 is an enlarged view in section and end elevation of the mechanism shown in Fig. 3;

45 Fig. 5 is an enlarged fragmentary detail view in plan of parts of the drive mechanism and control therefor; and

Fig. 6 is a view taken on the line 6—6 of Fig. 5;

50 Fig. 7 is a fragmentary view in front elevation of a number of conductor boxes in disassembled condition;

Fig. 8 to 8e, inclusive, are detail views in sectional elevation of various forms of feed indicators, and

Fig. 9 is an enlarged fragmentary view of part of an abrasive material distributing unit.

Referring first to the general assembly shown in Figs. 1 and 2 of the drawings, the sawing apparatus is here illustrated more or less diagrammatically, it being understood that the improved feeding mechanism may be used with any suitable type of machine. The frame of the sawing machine includes upright beams or columns 5 which are supported on a base 6 and 60 connected by cross beams 7, 8, 9 and 10. Pivotally suspended from the uprights 5 by means of bearing brackets 11, shafts 12, arms 13 and bar 14 are a plurality or gang of saws or cutters 15, which are shown partially through a 65 stone S, the latter being carried by a truck T adapted to travel on rails R. The arms 13 are shown as being reinforced by braces 13a fixed to the shaft 12. The saw-supporting members just specified constitute a carriage for the saws 70 15, which is adapted to be oscillated by any suitable means, that here shown being in the form of a crank 16 mounted on a drive shaft 17, the latter being supported by bearing pedestals 18. The crank 16 is connected to the 75 saws 15 by means of a pitman 19 and cross shaft 20 which is connected to the ends of the saws. The crank 16 may be driven from any suitable source of power, not shown.

As the saws 15 are oscillated in contact with 80 the stone they are intermittently lowered or progressed as they perform their cutting function, the means here shown being in the form of vertical threaded shafts 21 which are journaled in bearings 22 supported by the uprights 90 5, the bearings 11 for the saw being threaded on said shaft 21. At their upper ends, these shafts are provided with sprockets and sprocket chains 23 and 23a and driven in synchronism by means of bevel gears 24 and 25 and 24a and 25a, pulleys 26 and 26a, and a belt 27 which may extend to any suitable ratchet mechanism and be driven in synchronism with the main drive of the machine, as will be understood by those having knowledge of the art.

100 During the oscillation of the saws in contact with the stone S, they are supplied with cutting abrasive, generally in the form of a mixture of steel grit, sand, water and/or other abrasives. The means for supplying this abrasive material 105 embody the principal features of the present invention and will now be described.

Supported on the cross shafts 8 are hoppers 28 and 29, the hopper 28 being the main feed hopper, while the hoppers 29 constitute auxil- 110

ary feed hoppers. These hoppers are provided with bottom walls which form receptacles 28a and 29a for the material passing by gravity from the bottom outlets of said hoppers. The hoppers are supplied with suitable abrasive material, such as chilled shot and/or sand or the like. Extending adjacent the outlet of the main feed hopper 28 and journaled at opposite ends in bearings 30a supported on a suitable frame structure is a shaft 30, and on this shaft a plurality of impeller or feed wheels 31 are secured, each of which is formed with a series of feeding teeth or buckets 31a, note Fig. 4. These feed wheels pick up the material passing from the hopper 28 into the bottom receptacle 28a and deliver a suitable quantity thereof to conductor boxes 32, there preferably being one of these boxes for each saw, or kerf formed by the saw. Due to the tooth type of feed, the material is delivered in an even manner. From the conductor boxes the abrasive material falls by gravity into conductor pipes or tubes 33. To permit adjustability of these conductor pipes in accordance with the spacing of the saw kerfs they are provided with flexible or universal joint connections 34, thus permitting said pipes to be turned to various positions with respect to the stone, note particularly Figs. 2 and 4, and to permit adjustability as to height, said tubes are telescoped, as at 34a, and provided with means for maintaining the proper adjusted position such as the set screws 34b.

A feature of the present invention resides in an auxiliary abrasive material supply feed in conjunction with the main feed hopper 28. This auxiliary feed consists of a plurality of the hoppers 29, above specified, which have extending therethrough a shaft 35, the latter being journaled at opposite extremities in bearings 36. The hoppers 29 are adjustable longitudinally of the shaft 35, and mounted on said shaft and adapted to rotate in the receptacle 29a of each hopper are feeding wheels 37, provided with feeding teeth or buckets 37a, said wheels 37 being splined for longitudinally sliding movement on the shaft 35, the latter being formed with a longitudinally keyway 35a to accommodate this adjustment. The hoppers 29 are adjustably supported on cross beams or channels 38, each of said hoppers being provided with a base bracket 39 having mounted therein a screw 40 provided with a handle 41. The screw 40 is adapted to clamp against one of the channels 38. It will be seen that by loosening the screw 40, any one of the desired hoppers 29 together with its feed wheel 37 may be adjusted along the row of conductor boxes 32 to augment the supply of abrasive material fed to said boxes. Each conductor box is provided with a cover 42 which is pivoted at the apex of said box and may be thrown to either side of the latter as desired. In the position shown in Fig. 4, the cover is in a substantially vertical position and permits feed of abrasive from both main and auxiliary hoppers at the same time. When slid into closed position on either side of the conductor it prevents abrasive from feeding on the closed side. Thus both sides may remain open or either side may be open and the opposite side remain closed.

The conductor box assembly is supported on a cross bracket 43, in turn supported on the structural members 8. These boxes are shown in enlarged detail in Fig 7. The boxes on each end of the row are formed with lugs 44 while the in-

termediate boxes are formed with complimentary segmental lugs 45. The boxes are bolted directly to an angle bracket 46, see Fig. 4, by means of bolts 47. In assembling, the intermediate boxes are positioned side by side and then clamped together and secured to the bracket 46 by bolts and clamp washers, or the like, while the end boxes are secured against displacement by being bolted to the angle bracket 46. This construction facilitates casting and assemblage of the boxes and ensures retention in an assembled position with a minimum number of parts.

The means for driving the feed wheels 31 and 37 is particularly constructed with a view towards permitting an accurate predetermined feed at all times. Both sets of feed wheels are driven and controlled in substantially the same manner as particularly shown in Figs 3, 5 and 6. The shaft 30 in the main feed hopper 28 is provided at one end with a gear 48 adapted to be driven from a gear 49 secured on a shaft 50 journaled in bearings 51 fixed to a cross support 52. The outer end of the shaft 50 has secured thereon a friction disc member 53, note particularly Fig. 5, and the shaft 50a for the auxiliary feed has secured thereon a friction disc member 53a. The drive is applied to these friction members by means of a cross shaft 54 which is journaled in bearings 55 and has mounted thereon, in splined sliding engagement therewith, friction members 56 and 53a, adapted to contact with the discs 53 and 53a and rotate the latter. To enable the speed to be readily varied, the friction members 56 are shiftable longitudinally on the shaft 54, each member being provided with a grooved collar 57 in which a clutch fork 58 engages, the clutch fork being secured to a rack 59 slidably mounted in a guide bracket 60, which may be carried by any convenient stationary supporting member. The shafts 50 and 50a together with the discs 53 and 53a thereon are depressible longitudinally, each shaft being provided with a spring 61, bearing collar 62 and adjusting and supporting collar 63. The shaft 35 is preferably provided with a gear which engages a long faced gear on the end of shaft 50a to permit this depressing action without affecting the part of shaft 35 extending through the hoppers 29. The rack 59 is provided with a cam projection 65, adapted to contact with a cam member or yoke 66 which is formed with a boss or pin 66a extending into the shaft 50.

The foregoing speed varying assembly is duplicated for both the main and auxiliary feeds, as above specified, so that the detailed showing in Figs. 5 and 6 is illustrative of both devices as will be noted in Fig. 3. Each drive is separately controlled. The shaft 54 has secured on the end thereof a bevel gear 67 adopted to mesh with a gear secured on a shaft 68 which has secured thereon a drive pulley provided with a belt 70 extending to a suitable source of power not shown. Extending vertically with respect to the machine are shafts 71 and 71a, note particularly Fig. 1, which are provided on their upper ends with pinions 72 adapted to engage the racks 59, the lower ends of said shafts 71 and 71a being provided with indicating segments 73, which are calibrated as clearly shown in Fig. 5. Handles 74 and 74a are secured on the lower end of the shafts 71 and 71a. By turning these handles in the proper direction, the racks 59 are caused to move by engagement with the

pinions 72 and move the friction drive members 56 and 56a or away from the centers of the friction discs 53 and 53a, the speed being increased or decreased accordingly as the friction wheels 56 and 56a are moved away from or toward the centers of said friction discs 53 and 53a. When the "stop" position is reached, as shown by the indicating segments 73, the cam 65 engages with the yoke 66 and depresses the friction disc 53 or 53a out of contact with the friction wheels 56 and 56a, depending, of course, on which control lever is being operated.

As the material passes from the conductor tubes 33 it drops by gravity into a plurality of trough shaped funnels 75, which are provided for each kerf formed by the respective saws. This material augments the supply of mixed sand, shot and water distributed from reservoirs 76, which are supported at intermediate points with respect to the saws and at a suitable distance above the latter. Each reservoir is provided with a plurality of openings, preferably 3 in number as indicated at 77 and 77a (Fig. 2), and the openings 77 being formed at an intermediate point in the reservoir while the openings 77a are formed at opposite ends thereof. As the material passes or flows through these openings, it falls onto a main distributing baffle or sprinkler generally indicated at 78 and particularly shown in top plan in Fig. 9. The baffle 78 as shown is a roof-like structure which may be made of boards, sheet metal or the like, and gradually slopes from the center of the machine toward each side thereof. Spaced adjustable baffles or guides 78a are pivotally mounted on top of the main baffle or sprinkler 78 by means of pins 79, so that they may be adjusted to varying angular positions as shown in dotted lines on the one side of Fig. 9. It is preferred to adjust the guides 78a so that, starting from the reservoir 76, their adjacent ends will be spaced a certain distance apart and then gradually close until they meet at the outer end of the main baffle or sprinkler. Thus as the fluid-like mass falls on the main baffle 78, it is spread and falls evenly over the sides thereof as it flows toward the outer ends of the sprinkler, the last set of guides 78a stopping the outward flow of the final remaining material and directing it over the sides of the said sprinkler or main baffle 78. As the material falls from sides of the baffles 78, it strikes auxiliary distributing baffles 80 which are also adjustable. To provide for this adjustment, these auxiliary baffles 80 are pivotally mounted or hinged as at 81 and engaged at their outer edge by racks 82 carried by a cross head 83. These auxiliary distributing baffles 80, as shown, are in the form of a plurality of spaced cleats, the material falling onto the cleats and passing through the spaces therebetween. By adjusting the incline of these auxiliary distributors 80, a very efficient distribution of the material may be obtained.

Means are provided for indicating at a glance whether or not a proper supply of abrasive material is passing through each conductor pipe 33, this means being shown in various forms in Figs. 8 to 8e, inclusive. Referring first to Fig. 8 and 8a, the device consists of a wheel 84 which is mounted in a housing 85 on a shaft 86 coupled in the tube 33 or any other part of the conductor box assembly. The wheel 84 is provided with blades of the shape shown, or said blades may be given any desired shape. As the material falls through the conductor pipes it

strikes the blades of the indicator wheel 84 and revolves the latter. A meter may be affixed on the shaft 86 on which said wheel is mounted, or the housing may be partly open to show the speed of revolution of the wheel.

In Figs. 8b and 8c, the indicating device consists of a pivoted member 87 having an indicating disc 88 on the one end thereof adapted to rest against the housing 85 in its extreme lowered position. When the sand falling through the conductor pipe 33 strikes the member 88 it raises and lowers the disc 88 in accordance with the quantity of sand falling therethrough. The indicator is mounted on a shaft or pin 86 as in the forms shown in Figs. 8 and 8a.

In Fig. 8d, another type of indicator is shown. In this instance the device is in the form of a flat plate or disc 89 which is pivoted or hinged-mounted on a pin 86a secured to the lower end of the pipe 33. The weight of the disc 89 is such as to normally maintain it in an inclined position over the pipe 33. The material falling through the pipe 33 strikes the face of the disc 89 and oscillates the latter according to the quantity of material falling through said pipe. In Fig. 8e the conductor pipe is cut away at its lower end as shown to give a visual indication of the flow of material.

From the foregoing the operation of the mechanism will be readily understood. Briefly summarized, the stones S are loaded onto trucks T and moved up into cutting position with respect to the gang saws 15. The latter are then oscillated and intermittently lowered by the drive connections shown in Fig. 1 to cut the stone into blocks of various size, as desired. During this operation abrasive material and water is supplied to the saws.

The supply of mixed abrasive material and water is carried around in a continuous cycle and is continually being replenished with dry material from the hopper 28 and, when required, from the hopper 29. Below the machine is a sump 90 and conduit 90a, the latter leading into a well 91 provided with an overflow conduit 92 for carrying off powdered stone floating on the water. A supply pipe 92 and a hopper 94 are provided for adding water and sand when required. A pump 95 forces the material back up to the reservoir 76 through a pipe or conduit 96.

The abrasive material and water from the reservoirs 76 falls onto and through the distributing apparatus heretofore described and then onto the stone and into the kerfs formed by the saws, while the dry fresh replenishing supply of chilled shot, sand or like material is taken from the hopper 28 by the feed wheels 31 and falls into the conductor boxes 32 and passes down through the tubes 33 into the guide funnels 75. Should any particular saw or saws require additional abrasive material, it is only necessary to adjust the auxiliary hoppers 29 to the desired point with respect to the proper conductor box or boxes and throw the control handle 74a to running position, the quantity being easily controlled by adjusting the speed of the wheels 37. Thus, any saw or saws which may be lagging due to insufficient abrasive material can be brought up to the desired cutting speed.

The main feed from the hopper 28 may be readily adjusted by turning the handle 74 and varying the speed of the friction disc 53. Due to the relatively large number of teeth 32 on the wheel 31, the supply of material from the main

hopper 28 to each conductor box 32 is substantially constant and in proportion to the speed of the drive. Any number of auxiliary feed assemblies or hoppers 29 may be provided, and 5 other obvious modifications adopted within the scope of the invention as defined by the appended claims.

What we claim is:

1. Mechanism for feeding abrasive material to 10 stone cutting saws comprising a main feed hopper, a plurality of feed wheels in said hopper, means for conducting material from said hopper to the saws, and one or more auxiliary feed devices adjustable and co-operatively mounted 15 with respect to said main feed hopper for selectively delivering material to said conducting means.

2. Abrasive feeding mechanism for stone saws comprising a main feed hopper, a plurality of 20 rotatable impeller wheels in said hopper, conductor boxes arranged to receive the material from said impeller wheels, and one or more auxiliary feed hoppers adjustably mounted with respect to said conductor boxes for selectively 25 augmenting the supply of material delivered thereto.

3. Abrasive feeding mechanism for stone saws comprising a hopper, a plurality of impeller wheels rotatably mounted in said hopper, individual conductor boxes for each impeller wheel, one or more auxiliary feed hoppers also provided with impeller wheels mounted to co-operate with said main hopper, means for driving said impeller wheels, and means for adjusting 30 the drive of said wheels to vary the quantity of material delivered from said hoppers to said conductor boxes.

4. A mechanism for feeding abrasive material to stone saws, comprising a main feed hopper, a plurality of impeller wheels rotatably mounted in said hopper, one or more auxiliary feed hoppers also provided with impeller wheels mounted to co-operate with said main hopper, means for driving the impeller wheels of both 40 hoppers, and independent means for adjusting the drive of said main and auxiliary wheels.

5. A mechanism for feeding abrasive material to stone saws, comprising a main feed hopper and one or more auxiliary feed hoppers mounted to co-operate with said main feed hopper, impeller wheels rotatably mounted in said main and auxiliary hoppers, independently operating co-acting friction members for driving the impeller wheels in said main and auxiliary feed hoppers, and independently adjustable control mechanism for adjusting the drive 50 of said friction members.

6. A mechanism for feeding abrasive material to stone saws, comprising a main feed hopper having a plurality of abrasive outlets, an auxiliary hopper adjustably mounted for movement longitudinally of said main hopper and adapted to co-operate with said main feed hopper whereby the supply of abrasive material 60 from any one of the main feed hopper outlets may be augmented, conductor boxes arranged to receive the material from said hoppers, and conductor tubes connected to said conductor boxes, said conductor tubes being provided with flexible connections to permit adjustment thereof.

7. In a stone cutting machine, mechanism for feeding abrasive material, comprising a main feed hopper, means for discharging abrasive from 70 said main feed hopper to a plurality

of points of application, an auxiliary feed hopper mounted to co-operate with said main hopper, a support for said auxiliary hopper, and means for adjustably securing said auxiliary hopper to said support whereby said auxiliary hopper may be selectively positioned to increase 80 the quantity of abrasive fed to any one of said points of application.

8. In a stone cutting machine, a main feed hopper provided with a bottom wall forming a receptacle for abrasive material, one or more auxiliary feed hoppers also provided with bottom walls forming a receptacle for abrasive material and adjustably mounted with respect to said main hopper, individual conductor boxes adapted to receive the material from said receptacles, a plurality of toothed wheels for delivering the material from said receptacles to said conductor boxes and means for independently controlling the speed of rotation of the toothed 95 wheels in the main and auxiliary hoppers.

9. In a stone sawing machine, mechanism for feeding abrasive material to a plurality of saws, comprising, a main feed hopper for abrasive material, a plurality of main feed wheels adapted 100 to discharge abrasive material from said main feed hopper, a plurality of conductor boxes adapted to receive material discharged from said main hopper by said main feed wheels, an auxiliary feed hopper adjustably supported with respect to said main hopper, an auxiliary feed wheel in said auxiliary hopper, said auxiliary hopper and feed wheel being adapted to be selectively positioned to discharge abrasive material into any one of said conductor boxes. 110

10. In apparatus of the class described, a plurality of stone saws, conductor tubes adapted to deliver abrasive material to said stone saws, conductor boxes disposed at the inlet ends of said conductor tubes and means for delivering 115 abrasive material to said conductor boxes including a main feed hopper, a shaft extending longitudinally of said hopper, a plurality of feed wheels mounted on said shaft and adapted to discharge abrasive material from said hopper into said conductor boxes and an auxiliary hopper and feed wheel adjustably mounted with respect to said conductor boxes whereby the supply of abrasive delivered to any of said conductor boxes by the main feed wheel may be 120 augmented by abrasive material feed from the auxiliary hopper by the auxiliary feed wheel.

11. In apparatus of the class described, a plurality of abrasive material conductors disposed transversely across and above the work bed of a 130 stone saw, means for supplying abrasive material to said conductors comprising a main feed hopper, a plurality of main feed wheels adapted to deliver abrasive material from said main hopper to said conductors, and an auxiliary feed 135 hopper and feed wheel mounted for movement relative to said conductors whereby said auxiliary hopper and feed wheel may be positioned to supply abrasive material to any one of said conductors.

12. In apparatus of the class described, a plurality of abrasive material conductors disposed transversely across and above the work bed of a stone saw, means for supplying abrasive material to said conductors comprising a main feed hopper, a plurality of main feed wheels adapted to deliver abrasive material from said main hopper to said conductors, an auxiliary feed hopper and feed wheel mounted for movement relative 145 to said conductors whereby said auxiliary hopper 150

per and feed wheel may be positioned to supply abrasive material to any one of said conductors, means for driving said feed wheels and independently adjustable means for varying the speed of rotation of said main feed wheels and said auxiliary feed wheel.

5 13. In a stone cutting machine having a plurality of cutting saws, mechanism for feeding abrasive material to said saws, including abrasive material distributing means adapted to feed substantially equal amounts of abrasive material to each of said cutting saws and auxiliary abrasive material feeding means adapted to be selectively positioned to augment the supply of abrasive material to one of said cutting saws.

10 14. In a stone cutting machine, a gang saw having a plurality of blades, means for imparting sawing movement to said gang saw, and means for feeding abrasive to said blades, said feeding means including a main feed hopper provided with a plurality of independent feeding devices for distributing substantially equal quantities of abrasive material to each of said blades, and an auxiliary feed hopper adjustably supported whereby it may be selectively moved into position to augment the supply of abrasive feed to any one of said blades.

15 15. In a stone cutting machine, a gang saw

having a plurality of blades, means for imparting sawing movement to said gang saw, and means for feeding abrasive to said blades, said feeding means including a main feed hopper provided with a plurality of independent feeding devices for distributing substantially equal quantities of abrasive material to each of said blades, an auxiliary feed hopper adjustably supported whereby it may be selectively moved into position to augment the supply of abrasive feed to any one of said blades, and means for independently controlling the rate at which abrasive is fed from said main and auxiliary hoppers.

16. In a stone cutting machine having a plurality of cutting saws, mechanism for feeding abrasive material to said saws including abrasive material distributing means adapted to feed substantially equal amounts of abrasive material to each of said cutting saws, auxiliary abrasive material feeding means adapted to be selectively positioned to augment the supply of abrasive material to one of said cutting saws, and means for independently controlling the rate of feed from said main and auxiliary abrasive feeding means.
